United States Patent Office

Des. 184,374
Patented Feb. 3, 1959

184,374

KEY

Fred J. Russell, Los Angeles, Calif.

Application December 17, 1957, Serial No. 48,935

Term of patent 14 years

(Cl. D50—4)

Figure 1 is a side elevational view of a key, showing my new design.

Figure 2 is an end elevational view taken from the left of Figure 1.

Figure 3 is an end elevational view from the end opposite Figure 2.

Figure 4 is a top plan view.

Figure 5 is a side elevational view of the side opposite to that shown in Figure 1.

I claim:

The ornamental design for a key, as shown.
